COUPLER

Joseph Elliott and James Chalmers,
Winnipeg, Manitoba, Canada

Application December 1, 1933, Serial No. 700,581

4 Claims. (Cl. 280—33.15)

The invention relates to couplers, particularly designed for use on trailers and a general object of the invention is to provide a coupler which will permit a truck or towing vehicle to be quickly coupled to a trailer and which is arranged so that the coupler can be easily and quickly released from a distant point.

A further object is to design the coupler so that when backing up, any damaging back thrust will be absorbed in an abutment provided and also to arrange the locking parts so that there is no possibility of them becoming accidentally unlocked and the coupler thereby released.

A further object is to provide means for raising the coupling ring to guide it well up into the forward jaw of the rotary coupling member when the ring is initially pulled ahead, and thereby avoid any undue strain on the tip of such jaw.

20 A further object of the invention is to provide the rotary coupling member with a dog adapted to automatically lock the coupling member in working position and to supply the dog with a latch operating in the locked position of the coupling to positively prevent any accidental displacement of the dog.

25 A further object is to arrange the parts so that when the rotary coupling member is rotated by the coupling ring to coupled position, the dog and latch will automatically gravitate to their locking positions and such that when the latch is forcibly lifted it will raise the dog and release the rotary coupling member.

With the above more important objects in view, the invention consists essentially in the arrangement and construction of parts hereinafter more particularly described, reference being had to the accompanying drawings, in which:—

Fig. 1 is a perspective view of the coupler.

40 Fig. 2 is a side view thereof.

Fig. 3 is a vertical cross sectional view at 3—3

Figure 2.

Fig. 4 is a vertical sectional view at 4—4

Figure 3.

45 Fig. 5 is a sectional view similar to Figure 4 and showing the coupler in released position.

Fig. 6 is a horizontal cross sectional view at 6—6 Figure 2.

50 Fig. 7 is a vertical sectional view at 7—7 Figure 6.

Fig. 8 is a cross sectional view at 8—8 Figure 2.

Fig. 9 is a perspective view of the latch.

55 In the drawings like characters of reference

indicate corresponding parts in the several figures.

The body member 1 of the coupler is provided centrally with a pair of opposing spaced similar forwardly extending arms 2 and 3 and has upper and lower horizontally disposed reinforcing flanges 4 and 5 at the outer sides of the arms, one of the lower flanges being supplied with a hook 6. A stationary jaw 7 extends forwardly from the body member in a location centrally below the arms, the rear part of the jaw being stepped as shown best in Figures 4 and 5 to provide a vertical shoulder 8 for a purpose later disclosed. Centrally and rearwardly the body member is supplied with an upwardly extending transverse flange 10 having a horizontal shoulder 11 provided at the base thereof. The front face 12 of the flange is engaged by a dog later described.

The jaw 7 is supplied in advance of the shoulder 8 with an up curving guide finger 13 which cooperates with the parts later described. The body member when in use is fastened such as by bolts 14 permanently to the forepart of a trailer, truck or the like as indicated at 15.

The forward ends of the arms carry a stout pivot pin 16 on which we mount rotatably a rotary coupling member 17. The coupling member is provided with a forward jaw 18 on its under side which is adapted to overlie the forward end of the jaw 7 and with a pair of similar, spaced, rear jaws 19 and 20 which latter in the locked position of the rotary coupling member have their rear ends adapted to engage similar shoulders 21 presented by the body member and prevent further rotation in a clockwise direction of the coupling member. It will be observed that the jaw 18 and those 19 and 20 provide therebetween a curved passage for a coupling ring 22 carried at the rear end of a suitable draw bar 23, the jaw 18 at such time actually passing through the opening of the ring.

The upper part of the rotary coupling member is provided with a pair of spaced upwardly extending lugs 24 and 25 which are equipped with rearwardly disposed, upwardly and rearwardly inclined shoulders 26 for a purpose later disclosed. The lugs carry a pivot pin 27 on which we mount a gravity locking dog 28, the dog having its rear end of an inverted L-shape and adapted to normally engage the flange 10. The pin 27 is prevented from escaping by providing the arms 2 and 3 with upstanding flanges 29 and 30 which flanges are so shaped that they prevent end shift-

ing of the latter pin in all rotated positions of the rotary coupling member.

It will be observed that in the locked position of the rotary coupling member, the rear end of the dog is engaged with the vertical face 12 of the flange 10, the under side of the dog as such time resting against the shoulder 11 and that the dog has a natural tendency to gravitate to this position. In the locking position of the dog as shown in the principal views of the drawings, the lower tip of the jaw 16 is directly in advance of the finger so that the finger has a natural tendency to direct the forwardly pulled ring 22 upwardly to firmly engage the main body of the jaw 18 instead of the lower tip thereof which would be the natural tendency if such finger were not provided.

A locking latch 31 is pivotally connected by a pivot pin 32 to the rear part of the dog and such latch spans the dog and is provided with shoulders 33 adapted in the dog locking position of the latch to engage with the shoulders 26 already described. It is here explained that the inner faces of the lugs 24 and 25 are cut away to provide room for the side arms of the latch. The latch and dog are so arranged that when the dog is locking the rotary coupling member against rotation in a counter clockwise direction, the latch by engagement with the shoulders 26 is locking the dog against rotation in a clockwise direction. We have found that if a locking latch for the dog is not supplied, there is a possibility under normal road conditions of the dog jumping up due to road shock and releasing the coupler. With the latch supplied, this is impossible.

When it is desired to release the coupler, the forward tip of the latch will be raised to clear it from the shoulders 26 and then a lifting movement on the latch will cause the lifting of the dog to clear it from the flange 10 (see Figure 5).

The latch can be operated from a distance by attaching a pulling line to it, the pulling line being passed through the hole 34 of the latch and then tied. In the released position of the coupler, the free end of the latch rides the top face of the rotary coupling member.

In order that the invention may be clearly understood, we will now describe its operation assuming that the rotary coupling member and associated parts are in the position shown in Figure 5 and the ring of the draw bar is backed up to engage the lower jaws 19 and 20. As the ring engages the jaws and continues its back movement, it causes a clockwise rotation of the rotary coupling member, this continuing until the rear parts of the said jaws have engaged the shoulders 21. During this movement, the jaw 18 has been passed through the ring and has become caught in the transverse passage between the jaws 18, 19 and 20, the rear end of the dog has dropped under the action of gravity and has taken its locked position butted against the face 12 and resting on the shoulder 11 and the latch has gravitated to its locked position with the shoulders 33 thereof opposing the shoulders 26.

In the final position of the parts, the latch is locking the dog against rising and the dog is locking the rotary coupling member against rotation in a counter clockwise direction. Accordingly any subsequent forward pull of the draw bar is arrested by the jaw 18.

It will be observed that the hole 22 in the ring is large enough so that should the draught slacken, the ring of the draw bar will be guided back by the finger 13 and will strike the shoulder 8

at which time the forepart of the ring is clear of the front side of the jaw 18.

In order to subsequently release the coupler, it is only necessary to exert an upward pull on the free end of the latch as hereinbefore explained and this clears the dog and allows the coupling member to rotate under the forward pressure of the ring. By observing Figure 5, it will be noticed that in the released position of the coupling member, the dog prevents further rotary movement of the rotary coupling member in a counter clockwise direction and also acts due to its weight to hold the rotary coupling member in the position shown so that subsequent coupling of the ring is facilitated.

What we claim as our invention is:—

1. A coupler comprising a body member provided with a lower, centrally positioned, forwardly extending, stationary jaw and with a pair of forwardly extending, spaced arms above the jaw, a rotary coupling member positioned between the forward ends of the arms and pivotally carried thereby, said coupling member being provided at the front side with a forwardly extending upper jaw and a pair of spaced lower jaws underlying the same, said lower jaws spanning the stationary jaw aforesaid and said upper jaws being adapted to take a substantially vertical position adjacent to and overlying the stationary jaw in the clockwise rotation of the rotary member, a gravity operated, locking dog pivotally attached to the rear part of the rotary coupling member and normally riding the body member and adapted to take a substantially horizontal position and lock the rotary coupling member against counter-clockwise rotation upon the upper jaw of the rotary member taking a substantially vertical position as aforesaid and a gravity operated latch pivotally carried by the dog and engaging the rotary coupling member to positively lock the dog against accidental release in the locking position of the dog.

2. A coupler comprising a body member provided with a lower, centrally positioned, forwardly extending, stationary jaw and with a pair of forwardly extending, spaced arms above the jaw, a rotary coupling member positioned between the forward ends of the arms and pivotally carried thereby, said coupling member being provided at the front side with a forwardly extending upper jaw and a pair of spaced lower jaws underlying the same, said lower jaws spanning the stationary jaw aforesaid and said upper jaws being adapted to take a substantially vertical position adjacent to and overlying the stationary jaw in the clockwise rotation of the rotary member, a gravity operated, locking dog pivotally attached to the rear part of the rotary coupling member and normally riding the body member and adapted to take a substantially horizontal position with its rear end engaging the body member to lock the rotary member against counter-clockwise rotation upon the upper jaw of the rotary member taking a substantially vertical position as aforesaid and a gravity operated latch pivotally attached to the rear end of the dog and engageable with the rotary coupling member to positively lock the dog against accidental release in the locking position of the dog.

3. A coupler comprising a body member provided with a lower, centrally positioned, forwardly extending, stationary jaw and with a pair of forwardly extending, spaced arms above the jaw, a rotary coupling member positioned between the forward ends of the arms and pivotally carried

thereby, said coupling member being provided at the front side with a forwardly extending, upper jaw and a pair of spaced lower jaws underlying the same, said lower jaws spanning the stationary 5 jaw aforesaid and said upper jaws being adapted to take a substantially vertical position adjacent to and overlying the stationary jaw in the clockwise rotation of the rotary member, and having further a pair of rearwardly disposed side lugs 10 presenting locking shoulders, a gravity operated, locking dog pivotally carried by the lugs and normally riding the body member and adapted to take a substantially horizontal position with its rear end engaging the body member to lock the rotary 15 member against counter-clockwise rotation upon the upper jaw of the rotary member taking a substantially vertical position as aforesaid and a gravity operated latch pivotally attached to the rear end of the dog and having shoulders engageable with the shoulders aforesaid to positively 20 lock the dog against accidental release in the locking position of the dog.

4. In a coupler, in combination, a stationary body member having a lower, centrally positioned, forwardly extending, stationary jaw and a pair of shoulders at the sides of the jaw and the jaw provided with a vertical shoulder and a pair of forwardly extending spaced arms above the jaw and a rotary coupling member positioned between the forward ends of the arms and pivotally carried thereby, said coupling member being provided at the front side with a forwardly extending upper jaw and a pair of spaced lower jaws underlying the same, said lower jaws spanning the stationary jaw aforesaid and being adapted when rotated in a clockwise direction to engage the pair of shoulders aforesaid and said upper jaw 15 being adapted to take a substantially vertical position adjacent to and overlying the stationary jaw and opposing the shoulder of the stationary jaw when the lower jaws are engaging the pair of shoulders. 20
